UNITED STATES PATENT OFFICE.

ORSON P. STANFIELD, OF BAXTER SPRINGS, KANSAS.

CHAT DRAW-OFF.

1,358,122.

Specification of Letters Patent.

Patented Nov. 9, 1920.

Application filed October 21, 1919. Serial No. 332,144.

To all whom it may concern:

Be it known that I, ORSON P. STANFIELD, a citizen of the United States, residing at Baxter Springs, in the county of Cherokee 5 and State of Kansas, have invented certain new and useful Improvements in Chat Draw-Offs, of which the following is a specification.

This invention relates to chats separators 10 of the class ordinarily used in conjunction with the commonly known type of jiggers having series of compartments provided with vertically oscillating plungers for forcing water up through grates or screens.

15 The invention consists in providing an auxiliary compartment in conjunction with the ore discharge box of a separator in order that the chats layers may be drawn off from between the waste and ore layers—it being 20 understood that the effect of the separator is to classify or segregate the products dumped in the ore discharge box into distinct layers—the heaviest products generally the ore, being the lowest. A further embodiment of 25 the device effects an efficient and continuous scavenging of the chat separator by water, a conduit being provided with connections with a water main or service pipe.

Other objects of the invention are to construct a chat separator which may be applied to a jigger or separator and when desired dismounted therefrom in a very short time and without any great labor or exertion; and also to provide a device which may 35 be very quickly and easily manufactured at very small initial cost.

The above and additional objects are accomplished by such means as are illustrated in preferred embodiments in the accompanying 40 drawings described in the following specification and then more particularly pointed out in the claims which are appended hereto.

In the drawings wherein is illustrated the 45 preferred form of the invention:

Figure 1 is a transverse sectional view of an ore separator employing the present invention.

Fig. 2 is a detail perspective view of the 50 invention disassembled to illustrate clearly the several parts included in this construction.

In describing my invention in detail reference will be had to the accompanying 55 drawings wherein like characters designate

like or corresponding parts throughout the several views, and in which;

A designates generally one of a series of ore separator compartments having the usual oscillating plunger B and ore discharge box C within which is carried the chats separator designated in its entirety by D. A grating or screen E supports the ore and permits the entrance of water which is forced up through the ore by action of the plunger B with sufficient velocity to cause the various products to separate into layers; three of which I have indicated as ore, chats and waste. As this form of jigger or ore separator is of a well known type I have merely shown it here for the purposes of illustration.

The chats separator *per se* (for a detail view of which see Fig. 2) comprises a body portion 1 preferably of cast iron having an 75 interior cavity or chamber 2 the bottom 3 of which is inclined downwardly from one end to the other with sufficient pitch or fall to insure rapid flow of water and chats therefrom through an outlet opening 4 in the end 80 wall of the body portion communicating with the chamber 2 and having its lower edge flush with the bottom 3. The lower portion of the interior side wall of the body portion 1 is beveled or inclined downwardly adjacent 85 the opening 4 and a plurality of spaced apart alined screw threaded openings 5 are formed therein extending longitudinally thereof adjacent the upper edge of the body portion, for the reception of the screw threaded 90 terminals of a plurality of street L's or elbows 6 adapted to extend within the chats layer to draw off the chats therefrom. An inclined cover 7 having a plurality of bores 8 associated with other bores 9 in the body 95 portion and for registration therewith to receive suitable securing means such as bolts 10 is of the same length as the body portion but of a greater width providing an outstanding portion 11 resembling a flange for 100 disposition over an inclined or beveled edge of the ore discharge box C as is clearly illustrated in Fig. 1. In order that no leakage of water will take place between the cover and the body portion I have provided 105 a packing member 12 preferably formed of rubber disposed therebetween when the cover is placed thereupon.

As a means for scavenging the cavity 2 a conduit 13 is provided which communicates 110

therewith through a flanged opening 14, the said conduit being connected with a water main or service pipe having a suitable valve (not shown) for controlling the supply of water entering the chamber.

In operation the chat box constructed as above is placed on the interior of the ore discharge box C so that the street L's or elbows 6 extend within the chat bed, whereupon chats will be drawn off through the L's into the chamber 2 wherefrom they will be carried by the water issuing from the conduit 13. If found desirable, a suitable receptacle may be placed below the opening 4 to receive the chats upon their egress from the chats separator.

Attention is directed to the fact that the chat separator is held in place by its own weight, the inclined outstanding portion of the cover securely holding it in place through engagement over the beveled edge of the ore separator, however suitable auxiliary securing means may be provided in the form of bolts (not shown) if found desirable.

Obviously structural changes of a slight nature will be necessitated when this invention is reduced to practice and consequently I desire it to be understood that such changes may be made in the embodiment herein illustrated and described as fall within the scope of the appended claims.

What I claim is:

1. An attachment for ore-separators of the type indicated including a cast-iron body portion having a chamber formed therein, the bottom wall of the chamber inclined downwardly from one end to the other thereof, an outlet opening in the body portion communicating with the chamber, screw threaded openings in the body portion ad-

jacent the upper edge thereof and communicating with the chamber pipe elbows mounted in the openings for admitting chats or other ore-separator products to the chamber, a cover for the chamber, such cover being of approximately the same length as the body portion but of a greater breadth and inclined downwardly with respect to the body portion to engage upon one edge of the ore-separator to hold the attachment thereupon, and means communicating with the chamber through the cover for carrying the chats outwardly therefrom through the outlet opening.

2. An attachment for ore-separators of the type indicated including a body portion, having a chamber formed therein, an outlet opening in the body portion communicating with the chamber, the bottom wall of the chamber inclined downwardly from one end to the outlet opening, a plurality of spaced apart longitudinally aligned pipe elbows communicating with the chamber, a cover for the body portion inclined laterally with respect thereto, an outstanding portion of the cover disposed upon an adjacent wall of the separator to hold the attachment thereupon, a water inlet pipe extending through the cover and communicating with the chamber for carrying the chats or ore-products outwardly therefrom through the outlet opening, and packing between the cover and the body portion for preventing leakage of the contents of the chamber outwardly from between the cover and the body portion.

In testimony whereof, I affix my signature hereto.

ORSON P. STANFIELD.
